CLAIM

The ornamental design of the set of toggles, as shown and described.

DESCRIPTION

FIG. 1 is a front, top, right side perspective view of the set of toggles, showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear side elevational view thereof; and,

FIG. 7 is a front side elevational view thereof.

The broken lines in the drawings depict portions of the set of toggles that form no part of the claimed design.
